UNITED STATES PATENT OFFICE

171,896

LAMP BASE

Herman Kravitz, Chicago, Ill.

Application May 18, 1953, Serial No. 25,049

Term of patent 3½ years

(Cl. D48—20)

To all whom it may concern:

Be it known that I, Herman Kravitz, a citizen of the United States of America, residing at Chicago in the county of Cook and State of Illinois, have invented a new, original, and ornamental Design for a Lamp Base, of which the following is a specification, reference being had to the accompanying drawing, forming a part thereof, wherein:

Fig. 1 is a front perspective view of a lamp base, showing my new design; and

Fig. 2 is a rear perspective view thereof.

I claim:

The ornamental design for a lamp base, as shown.
